UNITED STATES PATENT OFFICE.

KARL HÜRTTLE, OF FRIEDRICHSHAFEN, BODENSEE, GERMANY, ASSIGNOR TO LUFT-SCHIFFBAU ZEPPELIN GESELLSCHAFT MIT BESCHRÄNKTER HAFTÜNG, OF FRIEDRICHSHAFEN, BODENSEE, GERMANY.

AIRSHIP.

Application filed February 11, 1925, Serial No. 8,352, and in Germany February 29, 1924.

My invention relates to airships, and more especially to rigid airships.

It is usual to have a network of strings loosely stretched inside the panels formed by the girders of the ship's hull. The gas cells inserted in the hull bear against this network. A certain bulging of the network is allowed, but this bulging must not exceed a certain margin which is given by 5 the outer cover stretched over the outside of the panels. On the other hand, it is of advantage to have some bulging because it increases the gas capacity of the cells. It is therefore desirable to provide for a fixed 10 amount of bulging. The ordinary string netting will expand while in use and will also be highly sensitive to moisture. This causes changes in the degree of bulging, which means that you have to provide for a 15 very low limit for bulging from the beginning. According to my invention, I improve these conditions by impregnating the strings with a substance which will reduce their elastic expansion. This limits the 20 margin in the possible changes of bulging. An impregnation of the strings with a substance which renders them less sensitive to moisture will work to the same effect. So, if such means are made use of in accord- 25 30 ance with my invention, the limit for bulging allowable from the beginning will be greater, which means greater gas capacity of the cell.

Having given a general description of 35 my invention, I now want to point it out more in detail referring to the drawing which represents an example embodying my invention.

Fig. 1 is part of a cross section of an 40 airship, and Fig. 2 represents a panel of the airship hull, in side view with the outer cover removed.

The letter L designates the longitudinal 45 members of the hull, over which the outer cover O is stretched. The wall of the gas cell is shown at G, and S are the strings against which the wall G bears and which are impregnated with a cellulose varnish, dope or the like to reduce their elasticity and 50 to render them less sensitive to moisture.

A is the air jacket between the wall of the gas cell G and the outer cover O. The bulging of wall G into this jacket must be limited according to the above description.

I do not want to be limited to the exact 55 details of the description, or the example shown in the drawing, as many variations will occur to those skilled in the art.

What I claim is:

1. Method of limiting the margin in the 60 bulging of gas cells in airships which consists in impregnating the strings constituting the network against which the walls of said cells bear with a substance adapted to reduce the elastic expansion of said strings. 65

2. Method of limiting the margin in the bulging of gas cells in airships which consists in impregnating the strings constituting the network against which the walls of said cells bear with a substance adapted to 70 render said strings less sensitive to moisture.

3. Method of limiting the margin in the bulging of gas cells in airships which consists in impregnating the strings constituting the network against which the walls of 75 said cells bear with a substance adapted to reduce the elastic expansion of said strings and to render said strings less sensitive to moisture.

4. Method of limiting the margin in the 80 bulging of gas cells in airships which consists in impregnating the strings constituting the network against which the walls of said cells bear with a cellulose varnish.

5. In a rigid airship, a hull, a compartment within said hull, a gas cell inserted in said compartment, a network of strings confining the bulging of the walls of said cell, said strings being impregnated with a substance which reduces their elastic expansion. 85 90

6. In a rigid airship, a hull, a compartment within said hull, a gas cell inserted in said compartment, a network of strings confining the bulging of the walls of said cell, said strings being impregnated with a substance which renders them less sensitive to 95 moisture.

7. In a rigid airship, a hull, a compartment within said hull, a gas cell inserted in said compartment, a network of strings con- 100

fining the bulging of the walls of said cell, said strings being impregnated with a substance which reduces their elastic expansion and which renders them less sensitive to moisture.

8. In a rigid airship, a hull, a compartment within said hull, a gas cell inserted in

said compartment, a network of strings confining the bulging of the walls of said cell, said strings being impregnated with a cel- 10 lulose varnish.

In testimony whereof I affix my signature.

KARL HÜRTTLE.
